Attorney.

UNITED STATES PATENT OFFICE.

JESSE BAILY, OF SPICELAND, INDIANA.

WASHING-MACHINE.

SPECIFICATION forming part of Letters Patent No. 276,329, dated April 24, 1883.

Application filed July 31, 1882. (No model.)

To all whom it may concern:

Be it known that I, JESSE BAILY, a citizen of the United States, residing at Spiceland, in the county of Henry and State of Indiana, have invented certain new and useful Improvements in Washing-Machines; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention has relation to improvements in washing-machines; and it consists in the construction, combination, and arrangement of the several parts, as will be hereinafter fully described, and specifically pointed out in the claims.

20 In the drawings, Figure 1 is a vertical section on line xx , Fig. 2. Fig. 2 is a plan view, and Fig. 3 is a detail view, as will be described.

A represents the tub, properly supported on legs a . The bottom a' of this tub is curved in the arc of a circle, as shown, and its sides $a^2 a^3$ project vertically upward therefrom.

25 $b b'$ represent the ends of the tub, which incline inwardly toward each other. The end b is made of equal height with the sides $a^2 a^3$, while the end b' is cut off below the top of the tub.

30 c is an offset extended from the end of the tub, and having its base c' arranged on a horizontal line connecting with the end b' and forming the shoulder c^2 . The end c^3 of the offset extends from the outer end of base c' up to a level with the top of the tub. I provide this offset in order to pivot the rubber-supporting arms farther away from over the tub, so that when the rubber is turned back in the position indicated in dotted lines, and which will be hereinafter described, they and the rubber will be out of the way, and will not prevent ready access to and the handling of the clothing being washed.

35 $d d$ represent vertical slats secured to and extending nearly the entire length of the ends $b b'$. These slats are arranged a slight distance apart, and permit the water to pass readily back to the bottom of the machine when it has been forced to the opposite ends

by the operation of the rubber hereinafter described.

40 e represents V-shaped slats having their lower sides flattened and secured on the bottom a' , and extending from side to side of the tub at right angles to the line of motion of the rubber. The upper surface of these slats is made concave in a curve corresponding to the curvature of the bottom a' , and with the motion of the rubber. This curvature aids to prevent the damage to the clothing, and also permits a steady movement of the rubber. The sides of these slats are beveled from top to bottom, making the slats V-shaped in cross section, and providing a space between them wider at the bottom than at the top, giving room for the water to settle after being pressed from the clothing, and the dirt will be accumulated between the slats and will not be disturbed or again thrown over the clothing, but remain in the bottom of the tub until it is drawn off therefrom, for which purpose I provide a hole properly plugged at one side of the tub. The slats e are placed a suitable distance apart so that four of them occupy a space corresponding to the length of space between the centers of the two end rollers, k , hereinafter described. The slats are placed equidistant apart, and by the arrangement described any two adjacent rollers will be supported on the first and third slats of a group while the third roller is passing over an intermediate space, and as the motion is continued the end rollers will be supported on the first and fourth slats while the middle roller is passing over the space between the two intermediate slats, thus securing a steadier and more even movement of the rubber on the base-slats.

45 f represents a box arranged at one side and extending the full length of the machine. It is adapted to hold the soap, wringer, &c.

50 $g g$ represent pivoted swinging rods having one end pivoted close to the sides $a^2 a^3$, within the offset c on rod g' , and their opposite ends extended to about midway the ends of the tub.

55 $h h$ represent the rubber bars or handles. They are provided with vertically-elongated slots h' , through which is passed the shaft i , which shaft extends through the ends of the bars g , and couples the said bars and the bars $h h$ together at a point intermediate the ends

of the handles or bars *h*, as shown. By pivoting the bars *h* within the slot *h'* the rubber thus supported accommodates itself more readily to the changes in washing.

5 *j* represents the semi-oval rubber, which is supported on the lower ends of the handles or bars *h*, as shown. This rubber is made about as wide as the body of the tub *A*, and its side boards *j' j'* are curved to correspond to the curvature of the bottom *a'*, and to the concavity in tops of slats *e*, as shown.

j' j' represent the presser-boards forming the ends of the rubber, and set at right angles to the axial line of the semi-oval rubber-frame.

15 These boards are provided with a series of perforations, *j*, through which the water flows back when the rubber is being forced from end to end of the tub in the operation of the device. These presser-boards, when the rubber 20 is forced against the ends of the suds-box, rest parallel to and coincide in their incline with the slats *d* on ends *b b*.

k k k represent the base-rollers. They are journaled in the board *j'*, so that their peripheries extend slightly below the lower edge of

25 the boards *j'*, and are made a suitable size to provide sufficient weight to press the dirt from the clothing, and they are arranged a slight distance apart, as shown, so that the water 30 will circulate freely from above and below through the intervening space in the operation of the device.

k' k' represent supplementary rollers made smaller than the rollers *k*, and journaled in the 35 side boards *j'*, immediately over the intervening space between the rollers *k*, and adapted to prevent the clothing from being forced up between the base-rollers and torn or otherwise damaged, and still not prevent the ready 40 flowing of the water through between the said rollers *k*.

l represents a latch for securing the bars *g h* when turned back in the positions shown in dotted lines. It is pivoted on top of the board 45 *c* to one side of one of the bars *g*, and is bent to provide the hooks *l' l'*, one on either side of the pivotal point. The hook *l'* is arranged to engage and secure the bar *g*, while the hook *l'* is adapted to secure the bars *h* when turned 50 back, as will now be described.

It will be seen that I pivot the bars *g* within the offset *c*, and that when the bars, with

the rubber, are turned back to the first position, marked *x*, (indicated in dotted lines, Fig. 1,) they will be secured by the hook *l'*, embracing the bar *g*. When turned back in this position the bars and the rubber will not interfere with any ordinary handling of the clothing, and when it is desired to turn the bars and rubber into the position shown in dotted lines 60 at *y*, Fig. 1, with the rubber elevated away from over the tub *A*, the bar *g* is held by one hook and the handle *h* by the other hook of the latch *l*, as described. The clothing, when it is forced against the ends *b b'*, which are made straight 65 and inclined inward over the tub, will fall back into the bottom of the tub when the rubber *j* recedes from the ends thereof, and the water which may be pressed upward from the clothes will be thrown inward toward the middle of the suds-box, and thereby the splashing of the water over the sides of the box is prevented.

The operation of the machine will be readily understood from the drawings and the description given. 75

Having thus described my invention, what I claim, and desire to secure by Letters Patent, is—

1. In a reciprocating-rubber washing-machine, 80 the rubber *j*, composed of the end boards *j' j'*, the vertical presser-boards *j' j'*, fixed on the opposite ends of the boards *j' j'*, and rollers *k k*, journaled in the side boards and between the presser-boards *j'*, and provided with a suitable 85 handle, *h*, substantially as set forth.

2. In a washing-machine, the combination of the suds-box, the bars *g*, having one end pivoted within the suds-box, the handle-bars *h*, carrying a suitable rubber and pivoted to the 90 swinging ends of the bars *g*, and the latch-bar *l*, pivoted on the suds-box, and having hooks formed on its opposite ends to engage one of the handle-bars *h* and bars *g* when the bars *h* have been inverted and turned down against the 95 side of the suds-box, substantially as and for the purposes set forth.

In testimony whereof I affix my signature in presence of two witnesses.

JESSE BAILY.
